UNITED STATES PATENT OFFICE.

JOSEPH J. WOZNACK, OF CHICAGO, ILLINOIS.

DESIGN FOR A CASING FOR A VEHICLE SIGNAL.

Application filed May 19, 1925. Serial No. 13,495. Term of patent 14 years.

To all whom it may concern:

Be it known that I, JOSEPH J. WOZNACK, a citizen of the United States, residing at Chicago, county of Cook, and State of Illinois, have invented a new, original, and ornamental Design for Casing for a Vehicle Signal, of which the following is a specification, reference being had to the accompanying drawing, forming a part thereof.

The figure is a perspective view of a casing for a vehicle signal showing my new design.

I claim:

The ornamental design for a casing for a vehicle signal, substantially as shown.

JOSEPH J. WOZNACK.
